DESIGN FOR A COMPOUND TOOL

Jacob J. Addin, Kalamazoo, Mich., assignor of
four-fifths to Leo Addin, Kalamazoo, Mich.

Application February 19, 1944, Serial No. 112,633
Term of patent 14 years

(CL. D54—13)

To all whom it may concern:

Be it known that I, Jacob J. Addin, a citizen of the United States, residing at the city and county of Kalamazoo, State of Michigan, have invented a new, original, and ornamental Design for a Compound Tool, of which the following is a specification, reference being had to the accompanying drawing, forming part thereof, in which—

Fig. 1 is a perspective view,
Fig. 2 is an elevational view looking from the left of Fig. 1, and

Fig. 3 is a cross section on line 3—3 of Fig. 1 of a compound tool, showing my new design.

I claim:

The ornamental design for a compound tool, as shown.

JACOB J. ADDIN.
